UNITED STATES PATENT OFFICE.

ADA LUZELLE WINN, OF HILLSBOROUGH, ARKANSAS.

BUTTON-FASTENER.

SPECIFICATION forming part of Letters Patent No. 376,497, dated January 17, 1888.

Application filed October 24, 1887. Serial No. 253,236. (No model.)

To all whom it may concern:

Be it known that I, ADA LUZELLE WINN, a citizen of the United States, residing at Hillsborough, in the county of Union and State of Arkansas, have invented a new and useful Improvement in Button-Fasteners, of which the following is a specification.

My invention relates to an improvement in button-fasteners; and it consists in the novel combination and arrangements of the parts thereof, which will be more fully hereinafter described, and particularly pointed out in the claim.

In the accompanying drawings, wherein like letters of reference indicate similar parts in the several views, Figure 1 is a perspective view of a piece of cloth having a button attached thereto by my improvement. Fig. 2 is a vertical sectional view of the cloth, with the button-fastener in elevation. Fig. 3 is a detail perspective view of the separate parts of my improvement.

My fastener consists, essentially, of the wire loop A and the securing-plate B. The loop A is formed from a single piece of wire, which is originally bent into U-shaped form, and is then bent to provide a loop, a, which passes through the button and cloth, and with short bends a', forming substantially right-angled extensions a² at the two ends of the said loop, the ends of said extensions forming points a³. From the short bends a' to the points a³ of the loop a gradual curve is formed, the said points a³ projecting slightly above the plane of the extension a².

The plate B is formed with four holes, b b', therein, and a reduced end projection, b², which is adapted to be bent upon the main portion of the plate.

The two ends of the loop A are passed 40 through the button and cloth and through the holes b in the end of the plate B, and then under the said plate. The plate B is then slipped up on the loop a and the points a³ brought into engagement with the openings b'. The 45 end b² is then bent over, as shown in Fig. 2, to prevent the points a³ tearing or wearing the fabric.

My device is intended especially for attaching suspender-buttons, and in such case the 50 length of the loop a should be such as to hold the plate away from the fabric sufficiently to permit the end b² being used as a hook to support the underclothes.

A button is readily attached by means of 55 my improvement, and time saved and a durable and strong connection obtained by the use thereof.

The utility of my device being obviously apparent, it is unnecessary to further enlarge 60 upon the same herein.

Having thus described my invention, what I claim as new is--

A button-fastener consisting of the staple A, having the loop a, the bends a', and the 65 lateral extensions a², provided with the points a³, and the plate B, having the apertures b b', fitted on the staple the bends a' being held in the apertures b and the apertures b' receiving the points a³, substantially as specified.

In testimony that I claim the foregoing as my own I have hereto affixed my signature in presence of two witnesses.

ADA LUZELLE WINN.
